FIG. 4.

FIG. 3.

FIG. 1.

UNITED STATES PATENT OFFICE.

FRANK ROME, OF LOMBARD, ILLINOIS.

RAILROAD-SIGNAL.

1,366,134.

Specification of Letters Patent. Patented Jan. 18, 1921.

Application filed October 4, 1920. Serial No. 414,529.

To all whom it may concern:

Be it known that I, FRANK ROME, a citizen of the United States, residing at Lombard, in the county of Du Page and State of Illinois, have invented certain new and useful Improvements in Railroad-Signals, of which the following is a specification.

This invention relates to railroad signals, and has for one of its objects providing suitable mechanism for operating a signal by trains as they approach crossings, and for the same train restoring the signal to its normal position after the train has passed the crossing; the arrangement being such when desired that the signal will be operated by a train coming in either direction. Other objects of the invention will be apparent from a consideration of the accompanying drawings and the following description thereof.

Of the drawings Figure 1 is a general perspective view of a railroad crossing and signaling mechanism which embody the features of my invention; Fig. 2 is a detailed view of the mechanism with portions thereof shown in cross-section; Fig. 3 is a sectional view along the line 3—3 of Fig. 2; and Fig. 4 is an elevation of one of the elements of the mechanism for operating the signal.

For the purpose of illustrating my invention I have shown it as applied to a railroad crossing. The train as it approaches the crossing automatically operates the mechanism so as to lower the signal which may consist of the ordinary sign "Stop" or at night it may be a red lantern. This signal is suspended from a rotatable arm 6 which is lowered as the train approaches to its on position and raised as the train leaves the crossing to its off position. Suitable mechanism connects the arm 6 with a track trip mechanism 7, or other suitable device, which is forced downwardly by the wheels of the train, and, by acting on an arm 8, rotates a rod 9, which, by means of another arm 10 fixed to the rod 9, moves longitudinally a rod 12. This rod in turn acts on an arm 13, fixed to a rotatable rod 14, to which is fixed a second arm 15. The arm 15 coacts with an arm 17 rotatably mounted on a rod 18. The rod 18 is slidably mounted in a vertical casing 19. A consideration of this mechanism will show that, as the track trip mechanism 7 is pushed downwardly, the arm 17 will be rotated; and, by means of a cam 20 fixed to the arm 17, and a coacting cam 16 fixed to the rod 18, the rod will be forced

downwardly by the cams. This movement of the rod 18 will cause the arm 6 to be operated in the following manner:

Mounted on the upper end of the casing 19 is a casing 21, inclosing a suitable mechanism for associating the rod 18 with the arm 6 so that, when the rod 18 is forced downwardly, the arm 6 will be lowered if it is in its raised position or it will be raised if it is in its lowered position and, in either case, the actuating force is a weight 22 supported by a cord which is wound on a drum 23. The drum 23 is loosely mounted on a shaft 24 which has fixed thereto a ratchet wheel 25. The weight 22 tends at all times to rotate the shaft 24, but the upper end of the rod 18, by means of the ratchet shoulders 26, prevent rotation of the shaft 24 until the rod 18 is forced downwardly by the train.

When the rod is forced downwardly, the upper end releases the shoulder 26, but the cams 20 and 16 quickly allow the spring 35 to force the rod 18 up so as to catch the next ratchet shoulder. The shaft 24 is thus released sufficiently to allow it, by the force of the weight 22, to make one fourth of a turn. This, by means of the cog wheels 27 and 28, rotates a shaft 29 one half of a turn, and this, by means of an arm 30, a link 31, and an arm 32, fixed to a shaft 33, operates the arm 6, which is fixed to the shaft 33, from its elevated to its horizontal or signaling position.

When the track trip mechanism 7 is pressed downwardly and the rod 12 forced horizontally, an extension 36 of the rod 12 will also be forced horizontally, to the right as shown in the drawing, and the track trip mechanism 37, which, with its connecting mechanism, is a duplication of the track trip mechanism 7, will be forced upwardly, it being understood that it is to be operated by the wheel of the train when the proper point is reached for elevating the signal. When this occurs the process will be merely the reverse of the above described process.

The weight 22 is supported in the casing 19, and as the casing 19 may extend underground as far as may be desired, the weight 22 will have a very material vertical movement; and, if sufficiently heavy will operate the mechanism many times before reaching its lower limit so as to be effective over a period of a day or a week as may be desired. But at suitable times the mechanism is rewound by means of a crank 40, detachably

connected to a shaft 41. A gear wheel 42 is fixed to the shaft 41, and this wheel coacts with a wheel 43 fixed to the drum 23, the wheel 43 and the drum being rotatably mounted on the shaft 24. As the weight 22 is elevated by the crank 40, a pawl 44, pivoted to the wheel 43, prevents the downward movement of the weight when the force of the operating crank is removed, by 10 coacting with the ratchet wheel 45 fixed to the shaft 24.

It is to be understood that suitable protecting means are provided for the track trip mechanism and other parts; and that 15 the various elements are constructed and adjusted so as to properly coact and produce the desired results; also that various modifications may be made in the mechanism by those skilled in the art, without departing from the spirit of my invention 20 as disclosed by the following claims. A pawl 46 coacting with the ratchet wheel 47 prevents backward rotation of the shaft 29; and a plate 48 covers the sign 5 when the 25 signal is raised.

I claim as my invention:

1. Train signaling means comprising a signal to be operated, a shaft for operating said signal, means tending to rotate said 30 shaft, means preventing the rotation of said shaft, means for rendering ineffective said preventive means so as to allow said shaft to operate said signal, said rendering means being operable by the wheel of a train, and

comprising a track trip mechanism positioned on one side of the signal, a track trip mechanism positioned on the other side of the signal, and means operatively connecting said mechanisms, each of said mechanisms arranged to be inoperative when the 40 other mechanism is operative.

2. Train signaling means comprising a signal to be operated, a shaft for operating said signal, a weight tending to rotate said shaft, means preventing the rotation of said 45 shaft, means operable by a train wheel for rendering temporarily ineffective said preventing means, and additional means for rendering ineffective said preventing means also operable by a train, each of said train 50 operable means being inoperative when the other of said means is operative.

3. Train signaling means comprising a signal to be operated, a shaft for operating said signal, a weight tending to rotate said 55 shaft, means preventing the rotation of said shaft, means operable by a train wheel for rendering temporarily ineffective said preventing means, second train operable means for rendering temporarily ineffective said 60 preventing means, said second train operable means being brought into operable position by the operation of said first mentioned train operable means.

In testimony whereof, I hereunto set my 65 hand.

FRANK ROME.
